CLAIM

The ornamental design for a self-service payment terminal, as shown and described.

DESCRIPTION

FIG. 1 is a first perspective view of a self-service payment terminal, showing our new design;

FIG. 2 is a second perspective view of the self-service payment terminal;

FIG. 3 is a front view of the self-service payment terminal;

FIG. 4 is a left side view of the self-service payment terminal;

FIG. 5 is a right side view of the self-service payment terminal;

FIG. 6 is a rear of the self-service payment terminal;

FIG. 7 is a top view of the self-service payment terminal; and,

FIG. 8 is a bottom view of the self-service payment terminal.

(Continued)

The broken lines in the drawings illustrate portions of the self-service payment terminal and its environment which form no part of the claimed design.

1 Claim, 8 Drawing Sheets
